UNITED STATES PATENT OFFICE.

FELIX GAIN, OF PARIS, FRANCE.

MEANS FOR VENTILATING RAILWAY AND OTHER CARRIAGES.

1,043,686.

Specification of Letters Patent.

Patented Nov. 5, 1912.

Application filed March 25, 1911. Serial No. 616,851.

To all whom it may concern:

Be it known that I, FELIX GAIN, subject of the Kingdom of Belgium, residing at 40 Rue de l'Arcade, Paris, in the Republic 5 of France, chief engineer of La Compagnie Internationale des Wagons-Lits et des Grands Express Européens, have invented certain new and useful Improvements in Means for Ventilating Railway and other 10 Carriages, of which the following is a specification.

The present invention has for its object a device for ventilating railway and other carriages which consists of a series of vertical 15 glass strips mounted on pivots in a frame which is mounted in the wall of the carriage, these strips being connected by a coupling rod which enables them to be displaced all together.

20 This invention relates at the same time, to controlling means for actuating the strips from the interior of the carriage and from the exterior, these means being devised in such a manner as not to constitute any appreciable 25 projection either internally or externally on the interior so as not to create any obstacle in the passages of corridor carriages and at the exterior so that the permissible external gage may not be exceeded.

30 In accordance with this invention operation from the interior is effected by means of a lever which is pivoted on a rigid bar fixed to the rotary shoes in which the upper and lower ends of one of the strips of glass are 35 embedded, the hinge of the lever being arranged in such a manner that the latter can be turned back vertically against the said bar; the extent to which the device projects is then so small that it does not impede the

40 passage of the window sliding vertically in the wall of the carriage. Operation from the exterior is obtained by means of a handle presenting the form of an inverted T which is fixed to the lower trunnion of one 45 of the strips beneath the frame of the device and outside the path of the movable window.

45 The accompanying drawing which is given by way of example only shows an embodiment of the invention.

50 Figure 1 is a partial elevation of the ventilating device from the inside. Fig. 2 is a vertical section on the line A—A in Fig. 1. Fig. 3 is a plan showing the top of the frame. Figs. 4 and 5 are respectively an elevation and a plan of one of the upper

shoes. Figs. 6 and 7 are respectively an elevation and a plan of one of the lower shoes. Fig. 8 is an elevation of a modified form of shoe presenting the form of a fork. 60

Each of the strips of glass 1 of the ventilator is held between two shoes 2 and 3 into which its top and bottom ends are let. Each of these shoes comprises a vertical trunnion 4 which ends in a head 5 of larger diameter. 65 These trunnions are supported in such a manner as to be able to rotate between upper cross pieces 6 and lower cross pieces 7 and bearings 8 which are fixed by means of screws to these cross pieces on their outer 70 face. The shoes are thus journaled upon the cross pieces in such a manner that they can not escape or be lost en route in case the glass should be broken. When a glass has to be replaced it is only necessary to withdraw the bearing 8 at the top or at the bottom 75 to enable a fresh glass to be placed in position in its shoes.

The cross pieces 6 and 7 are fixed in the wall of the carriage in any convenient manner at a certain distance outside the movable window 9 which slides in the wall in the usual manner. On its inner side the lower cross piece comprises an upwardly directed flange 10 which serves to prevent water from 80 entering the interior of the carriage.

The upper shoes 2 are provided with a lateral lug 11 presenting a recess 12; these recesses 12 serve for the reception of pins 13 integral with a connecting rod 14 which is 85 arranged between the lugs 11 and the upper cross piece 6; this rod is guided by pins 15 engaged in slots 16 formed in the cross piece 6. It follows that all the strips necessarily 90 rotate together.

The T-shaped ends of a vertical bar 17 are fixed by means of screws upon the shoes 2 and 3 of one of the strips; at approximately its middle point this bar carries an operating handle or lever 18. This handle 100 is pivoted upon the bar by means of a horizontal hinge in such a manner that it lies along the bar under the influence of gravity. In this position the projection that it forms on the inside of the strips 1 is so small that 105 it does not impede the passage of the sliding window 9 and its frame.

In addition the trunnion of one of the shoes 3 is prolonged downward and carries a handle 19 presenting the form of an inverted T which is located beneath the cross piece 7 and outside the path of the movable 110

window; this handle can be operated from the exterior by means of a portable rod ending in a fork which engages with the handle; it can also be operated from the interior of the carriage when the window 9 is lowered. The shoes which support the ends of the strips 1 may vary in shape. By way of example Fig. 8 shows a fork-shaped shoe in which the strip of glass 1 is held by a screw 10 passing through the whole.

Claim:

15 A ventilating device for cars, comprising upper and lower supporting members, the upper members being slotted, an upper and a lower set of shoes, each having projecting from one face a trunnion journaled in the said members, and a recess in its other side,

the upper shoes being provided with recessed lugs, strips having their ends in the recesses of the shoes, a bar arranged between the 20 upper member and upper shoes and provided with pins on its upper face engaging the slots of the upper member and pins on its lower face engaging the recesses of the lugs of the shoes, and means for turning the 25 shoes.

In testimony, that I claim the foregoing as my invention, I have signed my name in presence of two subscribing witnesses.

FELIX GAIN.

Witnesses:

CAMILLE BLÉTRY,
MAURICE ROUX.
